VOLTAGE REGULATOR CIRCUIT EFFECTIVE OVER PREDETERMINED INPUT RANGE

The present invention relates to a device which produces a constant output voltage at all times when variations in an input voltage are within a working range. More particularly, the invention is concerned with a transistor operated constant voltage device of the series connection type.

In a known constant voltage device of the series connection type, a control transistor connected in series to a main circuit is controlled by a difference in voltage between a voltage proportional to the output voltage and a voltage reference, so that the output voltage is kept constant when the input voltage remains within a given range. However, if the input voltage exceeds the upper limit of the working range, then the device fails to function as a constant voltage device and the output voltage increases. This may cause damage to a circuit element connected to the constant voltage device as a load.

In order to prevent this phenomenon, it has hitherto been customary to adopt the system of preventing the firing of the control transistor when the flow of output current (load current) is excessive as a result of a rise in the output voltage.

This system consists in connecting a resistor in series to the main circuit to prevent the firing of the control transistor by the voltage produced when an excess current flows through this resistor, whereby the output voltage is reduced to substantially zero. A disadvantage of this system lies in the fact that the control transistor is liable to be damaged or destroyed when the input voltage exceeds the maximum voltage level between the collector and emitter of the control transistor. To protect the control transistor against an excess voltage, a rapid acting fuse or an excess voltage relay has hitherto been used. However, the use of the former involves replacements each time the fuse melts while the use of the latter requires the use of an additional power source.

On the other hand, if the input voltage is reduced below the lower limit of the working range, then the device fails to function as a constant voltage device and the output voltage is reduced. For example, if the load is a computer, a reduction in the output voltage of the constant voltage device may result in a calculating error though the computer might operate as if it were normal.

The use of an undervoltage relay to prevent this error in operation also requires the use of an additional power source.

The present invention is based on the finding that better results can be obtained by reducing the output voltage to substantially zero when the input voltage is outside the working range. By this arrangement, it is possible not only to protect the control transistor against an excess voltage and an excess current but also to prevent an error in operation of the load because the load is not actuated. Moreover, the arrangement makes it possible to detect the abnormality as soon as it occurs.

Accordingly, an object of the present invention is to provide a constant voltage device whose output voltage is reduced to substantially zero when its input voltage is reduced below the lower limit of a working range of the device whereby an error in operation of the load can be prevented.

Another object of the invention is to provide a constant voltage device whose output voltage is reduced to substantially zero when its input voltage exceeds the upper limit of a working range of the device, whereby the device can be protected against an excess voltage and an excess current.

Still another object of the invention is to provide a constant voltage device which has a long service life and which is reliable in operation and economical to use, because the device is operated by purely electrical means without using a relay which requires an auxiliary power source and involves mechanical losses or fuses which require replacements whenever they melt.

Additional objects and advantages of the invention will become apparent from the description set forth hereunder when considered in conjunction with the accompanying drawings, in which:

FIG. 1 is a circuit diagram of a first embodiment of the device according to the present invention;

FIG. 2 is a diagrammatic representation of the characteristics of the device shown in FIG. 1;

FIG. 3 is a circuit diagram of a second device according to the present invention; and

FIG. 4 is a diagrammatic representation of the characteristics of the embodiment of FIG. 3.

The first embodiment of the device according to this invention which only provides for prevention of an error in operation of the load will now be explained with reference to FIG. 1.

In FIG. 1, a control transistor Tr1 is connected in series to a main circuit. A resistor R1 is connected across the collector and the base of said control transistor Tr1.

Voltage dividing resistors R3 and R4 for dividing an output voltage Eo are connected to the base of a detection transistor Tr2, and a Zener diode ZD1 which provides a voltage reference and a resistor R2 are connected to the emitter of the detection transistor Tr2. The collector of the detection transistor Tr2 is connected to the base of the control transistor Tr1, so as to thereby form a constant voltage circuit C of the series connection type.

The constant voltage circuit C operates in such a manner that the output voltage Eo is kept constant when variations in an input voltage Ei remain within a given range.

More specifically, a voltage proportional to the output voltage Eo is present across the voltage dividing resistors R3 and R4 which voltage is applied to the base of the detection transistor Tr2 where it is compared with the Zener voltage (voltage reference) of the Zener diode ZD1 to detect a variation in the output voltage Eo. The control transistor Tr1 which is controlled by the detected voltage operates to restore the output voltage Eo to a predetermined constant value by eliminating the variation.

If the voltage of the Zener diode ZD1 in the constant voltage circuit C is Ez1, the output voltage Eo will have a constant voltage Ec which is the sum of a voltage drop

$$\left(\frac{Ez1}{R4} \cdot R3 \right)$$

of R3 and a voltage drop (Ez1) of R4 when the input voltage Ei fluctuates within a given range, the voltage across the base and the emitter of the detection transistor Tr2 being disregarded. Therefore, the output voltage Eo can be expressed by the following equation:

$$E_o = Ez1 \left(1 + \frac{R3}{R4} \right) = E_c \quad (1)$$

The range of variations of the input voltage Ei which gives the output voltage Eo the constant value Eo obtained from this equation is the working range of the constant voltage device according to this invention as shown in FIG. 2.

The symbol S refers to a switching circuit which is a Schmidt circuit comprising transistors Tr3 and Tr4 and resistors R5 to R10 and utilizing the resistor R1 of the aforementioned constant voltage circuit C. A constant voltage element, for example a Zener diode ZD2, is connected in series to the base circuit of the first transistor Tr3 so as to prevent firing of the transistor Tr3 when the input voltage Ei is reduced below the lower limit of the working range.

More specifically, the Zener diode ZD2 is connected in series across the base of the first transistor Tr3 and the voltage dividing point where the input voltage Ei is divided by the resistors R5 and R6 in the circuit S.

The collector of said transistor Tr3 is connected through the resistor R7 to one input terminal a and through the resistors R8 and R9 to the other input terminal b.

The connecting point of the resistors R8 and R9 is connected to the base of the second transistor Tr4 whose collector is connected to the base of the control transistor Tr1 of the constant voltage circuit C. The emitters of the first and second transistors Tr3 and Tr4 are connected through the resistor R10 to the input terminal b.

The switching circuit S operates such that it reduces the output voltage Eo to substantially zero when the input voltage Ei is reduced below the lower limit E1' of the working range as

shown in FIG. 2. To enable the invention to be clearly understood, let us make the assumption set forth hereunder.

The assumptions may be inadequate for accurately determining the circuit constant, but they are best suited for clearly explaining the operation of the switching circuit S.

The assumptions are:

I. The voltage E_{be3} across the base and the emitter of the first transistor $Tr3$ and the voltage E_{be4} across the base and the emitter of the second transistor $Tr4$ as well as the voltage E_{ce3} across the collector and the emitter of the transistor $Tr3$ and the voltage E_{ce4} across the collector and the emitter of the transistor $Tr4$ are disregarded when the transistors $Tr3$ and $Tr4$ are fired; and

II. The Zener diode $ZD2$ has a very high nonworking impedance which is infinite, and the current flowing therethrough is disregarded. On the other hand, it has a very low working impedance which is substantially zero, and the current flowing thereto is of very high value and variations in the value of this current do not cause variations in the Zener voltage.

On these assumptions, the conditions under which the first transistor $Tr3$ is fired and the second transistor $Tr4$ is deenergized will be expressed by the following relationship:

$$\frac{R6}{R5+R6} \cdot Ei > Ee3 \left(= \frac{R10}{R1+R10} \cdot Ei \right) + Ez2 \quad (2)$$

where $Ez2$ is the Zener voltage of the Zener diode $ZD2$, and $Ee3$ is the emitter voltage of the transistor $Tr3$.

The reason why the relation mentioned above holds will now be explained. Since the conditions under which the transistor $Tr3$ is fired and the transistor $Tr4$ is deenergized are sought, $Tr3$ is deenergized and $Tr4$ is fired now.

The input voltage Ei is divided by the resistors $R5$ and $R6$, and also divided by the resistors $R1$ and $R10$ because the voltage E_{ce4} across the collector and the emitter of the transistor $Tr4$ is disregarded in accordance with the assumption set forth in (II) above.

Accordingly, the voltage of the resistor $R6$ can be expressed by

$$\frac{R6}{R5+R6} \cdot Ei$$

and the voltage of the resistor $R10$ or the emitter voltage $Ee3$ of the transistor $Tr3$ can be expressed by

$$\frac{R10}{R1+R10} \cdot Ei$$

If the voltage of the resistor $R6$ is higher than the sum of the emitter voltage $Ee3$ of the transistor $Tr3$ and the Zener voltage $Ez2$ of the Zener diode $ZD2$, a current flows across the base and the emitter of the first transistor $Tr3$ because of the voltage of the resistor $R6$, so that the resistance across the collector and the emitter of the first transistor $Tr3$ is lowered and consequently the transistor $Tr3$ is fired. In this case, firing of the first transistor $Tr3$ results in current not flowing across the base and the emitter of the second transistor $Tr4$, and the transistor $Tr4$ is deenergized.

The aforementioned relationship (2) can be rewritten as follows:

$$Ei > \frac{Ez2}{\frac{R6}{R5+R6} - \frac{R10}{R1+R10}} \quad (2')$$

When the input voltage Ei is such that the relation (2') holds, the first transistor will be fired and the second transistor will be deenergized.

Thus, the input voltage Ei exerts no influences on the constant voltage operation of the constant voltage circuit C in which the control transistor $Tr1$ is controlled such that a voltage proportional to the output voltage which is taken out by the voltage dividing resistors $R3$ and $R4$ is compared with a voltage reference and the variation in the output voltage is removed. It will readily be seen that the conditions under which the first transistor $Tr3$ is deenergized and the second transistor $Tr4$ is fired can be expressed by the following relation

$$\frac{R6}{R5+R6} \cdot Ei < Ee3 \left(= \frac{R10}{R1+R10} \cdot Ei \right) + Ez2 \quad (3)$$

In other words, the first transistor $Tr3$ will be deenergized and the second transistor $Tr4$ will be fired when the input voltage Ei can be expressed by the following relation:

$$Ei < \frac{Ez2}{\frac{R6}{R5+R6} - \frac{R10}{R1+R10}} \quad (3)$$

The voltage $Eb4$ (the voltage of the resistor $R9$) of the transistor $Tr4$ when it is fired is equal to its emitter voltage (the voltage of the resistor $R10$), because the voltage E_{be4} across the base and the emitter of the transistor $Tr4$ is disregarded in accordance with the assumption (I).

Therefore, the following relation will hold:

$$Eb4 = \frac{R10}{R1+R10} \cdot Ei$$

Also, when the current amplification degree of the $Tr4$ is $\beta 4$ with respect to the base voltage $Eb4$ of the transistor $Tr4$, the base current $Ie4$ of the transistor $Tr4$ can be expressed by the following relation:

$$Ie4 = \frac{1}{\beta 4} \cdot \frac{Ei}{R1+R10}$$

And the current $I9$ flowing through the resistor $R9$ can be expressed by the following relation:

$$I9 = \frac{1}{R9} \cdot \frac{R10}{R1+R10} \cdot Ei$$

Thus, the current flowing to the resistors $R7$ and $R8$ will be $Ie4+I9$.

Therefore, the conditions set forth below has only to be satisfied if the aforementioned relation (3') is to hold:

$$Eb4 + (R7+R8)(Ie4+I9) < Ei$$

$$\frac{R10}{R1+R10} \cdot Ei + (R7+R8)$$

$$\left(\frac{1}{\beta 4} \cdot \frac{Ei}{R1+R10} + \frac{1}{R9} \cdot \frac{R10}{R1+R10} \cdot Ei \right) < Ei$$

$$\therefore \frac{R10}{R1+R10} \left(1 + \frac{R7+R8}{R9} \right) + \frac{R7+R8}{\beta 4(R1+R10)} < 1 \quad (4)$$

If the values of the resistors $R7$ and $R8$ are selected such that the sum thereof is substantially equal to the value of the resistor $R9$ so that $R1 > R10$, the aforementioned relation (4) will be simplified as follows:

$$\frac{R7+R8}{\beta 4 R1} < 1 \quad (4')$$

What is important in the formula (4) or (4') is that the second transistor $Tr4$ can be fired by merely setting the circuit constant of the switching circuit S irrespective of the input voltage Ei . Therefore, if the circuit constant is set such that the aforementioned relation (4') holds, the second transistor $Tr4$ will be fired when the input voltage satisfies the conditions (3'). Firing of transistor $Tr4$ results in the current flowing through the resistor $R1$ being shunted to the transistor $Tr4$, so that almost no current flows to the base of the control transistor $Tr1$. This deenergizes the control transistor $Tr1$, and the emitter voltage of the control transistor $Tr1$ or the output voltage Eo becomes substantially equal to the base voltage of $Tr1$.

$$\text{or } Ee1 = \frac{R10}{R1+R10} \cdot Ei$$

because the voltage E_{be1} across the base and the emitter of the transistor $Tr1$ is disregarded.

Thus, the output voltage will be reduced to substantially zero when $R1 > R10$. If the marginal value Ei' of the input voltage that permits the relation (2') or (3') to hold is such that $Ei' > Ei$, then $Eo=0$. The value Ei' will thus be the lower

When $E_o=0$, the emitter voltage E_e3 of the first transistor $Tr3$ becomes

$$\frac{R10}{R1+R10} \cdot Ei$$

because of the firing of the second transistor $Tr4$. Therefore, the conditions for maintaining the first transistor $Tr3$ deenergized and the second transistor $Tr4$ fired or $E_o \approx 0$ are

$$\frac{R10}{R1+R10} \cdot Ei \geq \frac{R10}{R7+R10}$$

Thus, $R1 < R7$. On the other hand, the conditions for maintaining the output voltage E_o at the level of a constant voltage value

$$Ec = Ez1 \left(1 + \frac{R3}{R4} \right)$$

will be as follows when the voltage across the collector and the emitter of the control transistor $Tr1$ is E_{c1} (When E_{c1} is zero, it is impossible to effect control):

$$Ei > E_{c1} + Ez1 \left(1 + \frac{R3}{R4} \right) \quad (5)$$

In this case, E_{c1} must be higher than the saturation voltage across the collector and emitter of the control transistor $Tr1$.

The saturation voltage across the collector and the emitter of a usual power transistor being less than 1 to 2 volts, the aforementioned relation (5) will be rewritten as follows when the minimum value of E_{c1} is assumed to be 3 volts on the safe side:

$$Ei \geq 3 + Ez1 \left(1 + \frac{R3}{R4} \right) \quad (5')$$

That is, the lower limit Ei' , if the input voltage can be obtained from the relation (5'), so that E' can also be expressed as follows:

$$Ei' = 3 + Ez1 \left(1 + \frac{R3}{R4} \right) \quad (6)$$

Thus, the output voltage of the constant voltage device will never be less than

$$Ec = Ez1 \left(1 + \frac{R3}{R4} \right)$$

When $Ei' < Ei$.

Assuming that the base current begins to flow to the first transistor $Tr3$ when $Ei=Ei'$, the following relation can be obtained from the aforementioned relation (2):

$$\frac{R6}{R5+R6} \cdot Ei' = \frac{R10}{R1+R10} \cdot Ei' + Ez2$$

If $k1$ and $k2$ are substituted for

$$\frac{R6}{R5+R6} \quad \text{and} \quad \frac{R10}{R1+R10}$$

respectively in the above relation, then the following relation can be obtained:

$$k1 = k2 + \frac{Ez2}{Ei'} \quad (7)$$

If the circuit constant is set such that the interrelation between $k1$, $k2$, $Ez2$ and Ei' permits the aforementioned relation (7) to hold, the states of the first transistor $Tr3$ and the second transistor $Tr4$ will be reversed so that the former is fired and the latter is deenergized when the input voltage Ei reaches the lower limit Ei' of the working range. When $Ei > Ei'$, $E_o \neq Ec$. Thus, the output voltage can be kept constant.

From the foregoing description, it will be appreciated that the present invention provides in one aspect a constant voltage device in which a control transistor connected in series to main circuit and having a resistor connected across the collector and the base thereof is controlled by a difference in voltage between a voltage proportional to the output voltage and a voltage reference so as to maintain the output voltage con-

stant when the input voltage remains within the working range.

The invention described with reference to the first embodiment thereof offers many advantages.

- 5 One of the advantages lies in the fact that since the output voltage is reduced to substantially zero when the input voltage is reduced below the lower limit of the working range, the load is not actuated so that any error in operation can be prevented. At the same time, the operator can readily and 10 quickly detect the abnormal condition.

The second advantage is that the use of no contacts results in the device which responds quickly, is reliable and stable in performance, and has a long service life.

- 15 The third advantage is that the use of the control transistor of the constant voltage circuit as a switching transistor for reducing the output voltage to substantially zero permits the use of transistors of small capacity in the switching circuit for controlling switching of the control transistor from the state in which it is fired to the state in which it is deenergized or vice versa. Thus, the device of this invention is low in cost and 20 therefore economical to use.

- 25 In the first embodiment of this invention having the construction and advantages described above, no means is provided for coping with that condition where the input voltage Ei is increased above its upper limit Ei'' or for coping with an increase in the output voltage Eo when the input voltage Ei is increased above the upper limit Ei'' . In the second embodiment shown in FIG. 3, means is provided for coping with such state.

- 30 Turning to the second embodiment, the circuit shown in FIG. 3 is substantially similar to the circuit shown in FIG. 1 except for the fact that a second constant voltage element, for example a Zener diode $ZD3$, for deenergizing the first transistor $Tr3$ when the input terminal is increased above the upper limit of the working range is connected in parallel to the resistor $R6$ which is connected across the base and the emitter of the first transistor whereby a switching circuit S' is formed.

- 35 It will be appreciated from the foregoing description that the second embodiment of the constant voltage device according to the present invention performs a constant voltage operation when the input voltage Ei shows variations within the working range as shown in FIG. 4 and that it reduces the output voltage Eo to substantially zero when the input voltage is reduced below the lower limit Ei' , provided that third assumption (III) is made in addition to the assumptions (I) and (II), said third assumption being that the nonworking impedance of the Zener diode $ZD3$ is very high that the current flowing thereto is substantially zero, and the working impedance of the Zener diode is very low and substantially zero with respect to the current flowing thereto, and the Zener voltage does not show any changes when there are variations in the current, and the Zener diode is not actuated when the input voltage is below the upper limit Ei'' of the working range. In other words, the relations (1) to (7) described above hold in the second embodiment too if the assumptions (I), (II) and (III) are made.

- 40 The second embodiment of the constant voltage device illustrated in FIG. 3 operates such that when the input voltage exceeds the upper limit of the working range ($Ei < Ei''$), the output voltage is reduced to substantially zero ($Eo \approx 0$).

- 45 The operation of this embodiment will be described hereinafter. In accordance with the assumption (III), the Zener diode $ZD3$ is not actuated when the input voltage is below the upper limit of the working range ($Ei < Ei''$), so that its impedance is infinitely high and the circuit operates as if the Zener diode $ZD3$ were not connected thereto. Thus, the second embodiment of the constant voltage device operates in the same manner as the first embodiment when the input voltage remains below the upper limit of the working range ($Ei < Ei''$).

55 In this state, the following relation holds:

$$Ez'1 = \frac{R6}{R5+R6} \cdot Ei = k1 Ei < Ez3$$

where $Ez'3$ is a terminal voltage of the Zener diode ZD3 and $Ez3$ is a Zener voltage of the Zener diode ZD3. Accordingly, if the value of $Ez3$ is determined such that $K1 Ei > Ez3$ when $Ei = Ei'$ then the Zener diode ZD3 is actuated when $k1Ei > Ez3$, whereby the terminal voltage $Ez'3$ (which is equal to $k1Ei$) of the Zener diode ZD3 can be maintained equal to the Zener voltage $Ez3$.

On the other hand, the emitter voltage $Ee3$ of the first transistor $Tr3$ when the latter is fired can be expressed by the following relation:

$$Ee3 = \frac{R10}{R7 + R10} \cdot Ei = k3Ei$$

where

$$k3 = \frac{R10}{R7 + R10}$$

A current does not flow to the base of the first transistor $Tr3$ when the sum of its emitter voltage $Ee3$ and the Zener voltage $Ez2$ of the Zener diode ZD2 is higher than the Zener voltage $Ez3$ of the Zener diode ZD3 or when the following relation holds:

$$k3Ei + Ez2 > Ez3 \dots \dots \dots (8)$$

Thus, the first transistor $Tr3$ is deenergized when the input voltage satisfies equation (8). Deenergization of the first transistor $Tr3$ fires the second transistor $Tr4$, thereby deenergizing the control transistor $Tr1$. Thus, the output voltage Eo is reduced to substantially zero in the same manner as when $Ei < Eiah$.

If the upper limit Ei'' of the working range at which $Eo=0$ when $Ei=Ei''$ is substituted for Ei in relation (8), the value of Ei'' can be expressed as follows:

$$Ei'' = \frac{Ez3 - Ez2}{k3}$$

From FIG. 4, it will be seen that $Eo=0$ when $Ei > Ei''$.

From the foregoing description, it will be appreciated that the present invention provides in another aspect a constant voltage device of the type described as the first embodiment of the invention which further comprises a second constant voltage element connected in parallel to the resistor which is connected across the base and the emitter of the first transistor, whereby the first transistor is deenergized when the input voltage exceeds the upper limit of the working range.

In addition to the advantages recited with reference to the first embodiment, it will be evident that the invention offers the advantages described hereinafter.

The fourth advantage lies in the fact that the constant voltage device according to this invention provides protection not only to the load against excess voltages and excess current but also to the control transistor against destruction, because the device operates such that when the input voltage exceeds the upper limit of the working range the output voltage is reduced to substantially zero and the switching circuit maintains the output voltage substantially in the zero level while the input voltage and current are divided.

The fifth advantage is that the load is not actuated when the input voltage exceeds the upper limit of the working range, because the output voltage is reduced to substantially zero when the input voltage is out of the working range. The operator can readily detect the abnormal condition.

In the present invention, the resistor $R10$ is a resistor for positive feedback that forms a Schmidt circuit.

This resistor is used for improving the characteristics of the device in actual use, and its use is not essential from the theoretical view point. The value of this resistor is preferably minimized, for if the resistor $R10$ has a high value the residual voltage of the output voltage will be correspondingly high when the control transistor is deenergized. Thus, the residual

voltage can be made substantially zero if $R7 \gg R10$ and $R1 \gg R10$.

It is to be understood that present invention is not limited to the specific circuits described as the first and second embodiments of this invention, and that many changes and modifications may be made therein within departing from the spirit and scope of the invention.

It is also to be understood that the invention covers any circuit that may derive from the embodiments described so long as it reduces the output voltage to substantially zero when the input voltage is reduced below the lower limit of the working range or out of the working range.

I claim:

1. A voltage regulator circuit for providing a constant output voltage when the input voltage thereto varies between a predetermined upper limit and a predetermined lower limit, the output of the voltage regulator falling to zero whenever the input voltage falls below said predetermined lower limit and rises above said upper limit, the circuit comprising:

- a. a voltage-regulating control transistor having a base, an emitter and a collector, the emitter-collector circuit thereof being serially connected between a first input terminal and a first output terminal of said voltage regulator to maintain said output voltage constant, the second input terminal of said voltage regulator being connected in common to the second output terminal thereof;
- b. a first transistor, having a base, an emitter and a collector, the collector of said first transistor being connected to said first input terminal;
- c. a second transistor having a base, an emitter and a collector, the collector of said second transistor being connected to the base of said voltage-regulating control transistor;

1. the emitters of said first and second transistors being connected to said second input terminal through a first resistor,

2. the base of said first transistor being connected to a tap on a voltage divider comprising a second and a third resistor serially-connected between said first and second input terminals,

3. the base of said second transistor being connected to the collector circuit of said first transistor, said first and second transistors and said first resistor forming a Schmidt trigger circuit with a fourth resistor which interconnects the base of said voltage-regulating control transistor to the collector circuit of said first transistor, and

d. a first constant-voltage device serially connected between the base of said first transistor and said voltage divider tap;

1. whereby, as the input voltage falls below said predetermined lower limit, said first constant-voltage device supplies a voltage to the base of said first transistor which turns said first transistor off, the action of said Schmidt trigger circuit then turning said second transistor on drawing base current from said voltage-regulator control transistor and switching it off, thereby terminating operation of the regulator.

2. The voltage regulator as set forth in claim 1, further comprising:

a second constant-voltage device serially connected in the base circuit of said first transistor, across said second resistor, whereby, as the input voltage rises above said predetermined upper limit, said second constant-voltage device switches to a low impedance condition turning off said first transistor, the action of said Schmidt trigger circuit then turning on said second transistor and drawing base current from said voltage-regulating control transistor to turn it off thereby terminating operation of said regulator.
